UNITED STATES PATENT OFFICE.

ARMIN POLLAK AND PHILIP F. TEISER, OF RICHMOND, VIRGINIA.

CIGAR.

SPECIFICATION forming part of Letters Patent No. 621,975, dated March 28, 1899.

Application filed August 31, 1898. Serial No. 689,946. (No model.)

To all whom it may concern:

Be it known that we, ARMIN POLLAK and PHILIP F. TEISER, citizens of the United States, residing at Richmond, in the county 5 of Henrico and State of Virginia, have invented new and useful Improvements in Cigars, of which the following is a specification.

Our invention relates to cigars; and it consists in a cigar comprising a bunch, a removable longitudinally-disposed fragrant tobacco-stem resting in the longitudinal center of the bunch and extended from the mouth end thereof, and a wrapper surrounding the bunch and the extended portion of the tobacco- 15 stem.

Irrespective of the material of which the stick is formed the invention consists in the combination of the bunch, a removable stick resting in the longitudinal center of the bunch 20 and extended from the mouth end thereof, and a wrapper surrounding the bunch and the extended portion of the stick whereby the end of the wrapper is held against casual un- 25 wrapping and the extended end of the stick is covered and the stick is held against casual movement or displacement.

The invention will be fully understood from the following description and claims when taken in conjunction with the annexed drawings, in which—

Figure 1 is a longitudinal central section of a cigar embodying our improvements. Fig. 2 is a detail view of the stick removed from the cigar. Fig. 3 is a longitudinal central 35 section illustrating a slight modification of the invention.

Referring by letter to said drawings, and more particularly to Figs. 1 and 2 thereof, A is the bunch of a cigar, B is the wrapper, 40 and C is the stick. The bunch A may be and preferably is composed of scrap-tobacco, which may be of an inferior grade, and is rolled or formed around the stick C, which preferably occupies the longitudinal center 45 of the cigar and is of a greater length than the bunch, so as to extend from that end of the same which is designed to be lighted slightly beyond the mouth end, as indicated by a. The wrapper B is applied to the bunch 50 in the usual manner, being rolled around said bunch and extended beyond the mouth end of the same in order to cover the extended

portion a of the stick, to which it is pasted, if necessary, to hold it against casual un- 55 wrapping and at the same time prevent casual movement or displacement of the stick.

The stick C may be formed of any suitable material, although fragrant material which will impart its fragrance to the tobacco and thus materially improve the flavor of the same 60 is preferred. A material eminently adapted to the purpose is the stem of Havana or other fine quality of tobacco-leaf, which, while easily procurable and cheap, is fragrant, and is calculated to impart its fragrance and fine 65 flavor to the inferior quality of tobacco composing the bunch A, and thereby materially improve the flavor of the cigar as a whole.

As before stated, the stick C is arranged to occupy the longitudinal center of the cigar. 70 Consequently it tends to hold the scrap-tobacco away from the longitudinal center of the cigar, where the same is liable to pack tightly, and when it is withdrawn it leaves a clear smoke-passage in the cigar and enables 75 the same to smoke freely. The stick also serves to lessen the liability of the cigar bending, and thereby prevents breaking of the wrapper, which ordinarily attends bending 80 of the cigar.

When it is desired to withdraw the stick C of tobacco-stem from the cigar, it is simply necessary to break the wrapper B at about the point marked b, when the portion a of the stem may be grasped in the fingers and 85 said stem easily pulled out of the cigar. This may be done without injury to the cigar and leaves the same ready to be smoked.

The construction shown in Fig. 3 is similar to that shown in Fig. 1, except that the extended portion a' of the stick C', with the wrapper covering the same, is bent so as to lie at right angles or approximate right angles to the main portion of the stem and the cigar and afford a finger-grasp to facilitate 90 the withdrawal of the stick from the cigar. Such bending of the stick of tobacco-stem 95 may be readily effected after the same is slightly dampened.

In the several embodiments of our invention the stick is tapered to a point at its inner end. This is done, when the stick is formed of a tobacco-stem, by moistening and rolling the stem to a point.

It is desirable to have the sticks tapered toward their inner ends, since it permits of their being easily withdrawn from cigars without liability of tearing or otherwise damaging the same.

Having described our invention, what we claim is—

1. In a cigar, the bunch, the tobacco-stem calculated to impart its fragrance to the tobacco forming the bunch; said stem occupying the longitudinal center of the bunch and extended beyond the mouth end of the same so that it may be drawn out to form a draft-passage, and a wrapper surrounding the bunch and the extended portion of the tobacco-stem, substantially as specified.
2. The combination in a cigar, of the bunch, a removable stick occupying the longitudinal

center of the bunch and extended beyond the mouth end of the same so that it may be drawn out to form a draft-passage, and a wrapper surrounding the bunch and the extended portion of the stick, substantially as specified.

In testimony whereof we have hereunto set our hands in presence of two subscribing witnesses.

ARMIN POLLAK.
PHILIP F. TEISER.
